UNITED STATES PATENT OFFICE.

FRED HENSEL, OF SAC CITY, IOWA.

DOOR CLOSER.

Application filed October 20, 1926. Serial No. 142,932.

The present invention relates to a door closer and aims to provide a structure which will prevent the slamming of a screen door or the like but will assure the tight closing of said door.

Another very important object of the invention lies in the provision of a device of this nature with a chain trained in a predetermined orbit and connected with a braking mechanism which will operate when the chain moves in one direction for retarding the movement of the chain, but which will be ineffective when the chain moves in the opposite direction.

Another very important object of the invention lies in the provision of a structure of this nature with means which is actuated upon the opening and closing of a door and which when actuated by the closing of the door will set into operation a braking mechanism for retarding the closing movement of the door and which when moved by the opening of the door will release the braking mechanism.

Another very important object of the invention lies in the provision of a device of this nature which is comparatively simple in its construction, inexpensive to manufacture, strong and durable, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:—

Figure 1 is a side elevation of the device embodying the features of my invention.

Figure 2 is a top plan view thereof with portions removed and showing another portion in section.

Figure 3 is a detail elevation of an initial buffer member.

Figure 4 is a detail elevation of a spring pressed member associated with said initial buffer member.

Figure 5 is an edge elevation of the member shown in Figure 4.

Figure 6 is a sectional view through the combined brake and clutch mechanism.

Figure 7 is a sectional view taken substantially on the line 7—7 of Figure 2 showing the spring operating mechanism.

Figure 8 is a top plan view of the device showing the same associated with a screen door or the like.

Figure 9 is a detail elevation of one of the sprockets, and

Figure 10 is a detail of the clutch.

Referring to the drawing in detail, it will be seen that the letter F denotes a U-shaped frame comprising side plates 5 and a bight 6. Flanges 7 extend inwardly from the upper edges of the plates 5. The plates 5 are provided adjacent the bight 6 with longitudinally extending slots 9 through which the axle 10 of a sprocket 11 extends. A U-shaped member 12 has its extremities pierced by the axle 10 and its bight pierced by a screw 14 so that the sprocket 10 may be adjusted longitudinally of the frame F. A second sprocket 15 is mounted on a shaft 16 journaled through openings in the sides 5. A chain 17 is trained over the sprockets 11 and 15. One of the links of the chain is provided with a stop projection 18. An angular member 19 is pivoted on said link as at 20, and has a downwardly projecting arm 21 and an arm 22 extending in the opposite direction for engaging a bell crank lever 23 through the lateral extension 24 on one end thereof, another lateral extension 25 being provided at the other end thereof and with which a spring 26 is engaged and said spring 26 is anchored on one side 5 as at 27. The spring 26 normally holds the member 19 in the position shown in Figure 1 when the door 28 is open. This door 28 is normally urged to a closed position in any suitable manner such as by a spring 29. The door 28 is provided with an arm 30 adapted to strike the arm 21 of the member 19 thereby causing the swinging of the member 19 and the stretching of the spring 26 for taking up the initial shock of the closing of the door. The projection or arm 30 will then engage another stop projection 31 on the chain 17 and urge the chain to move in its orbit about the sprockets 11 and 15, simultaneously rotating said sprockets as will be apparent. The chain 17 may be maintained taut through the action of the screw 14 as will be quite apparent without a more detailed description.

Associated with the shaft 16 I have provided a combined clutch and brake mechanism which I will now describe in detail. The shaft 16 extends beyond the sides 5 and one end thereof has mounted thereon a cylinder 33. A cam surface 34 is provided on

the cylinder 33 and a spring pressed member 35 is mounted in the cylinder 33 adjacent said cam surface 34 being normally projected outwardly therefrom. A disc 36 is loosely 5 mounted on the shaft 16 and has a casing 37 fixed thereto as at 38 for housing the cylinder 33 and functions as a drum. When the shaft 16 rotates in one direction, that when the door is closing, the cylinder 33 will rotate 10 in a counter-clock-wise direction as shown in Figure 6 thereby wedging the spring pressed member 35 between the cam surface 34 and the interior surface of the drum or casing 37 so that said casing and said disc will rotate 15 with the shaft 16, but when the shaft is rotating in the opposite direction it will be seen that this action will not take place, and therefore the shaft and the cylinder 33 will rotate while the drum or casing 37 remains 20 stationary.

A casing 39 is fixed to one side 5 and houses the drum 37 and the disc 36. On the disc 36 there is pivoted a pair of arcuate weight members 40 which are held inwardly 25 by a spring 41 engaged with the free end thereof. It will be seen, however, that when the disc 36 is rotated as heretofore indicated, because of the clutch engagement of the drum 37 with the cylinder 33, that centrifugal force will urge these weighted arms 40 outwardly to frictionally engage the interior of the casing 39, thereby causing the braking action to retard the motion of the shaft 16 and the motion of the chain 17 and 30 consequently retard the closing motion of the door 28 as will be apparent. In order to insure the closing of the door 28 I associate with the other end of the shaft a coil spring 42 which has one end anchored thereto and 35 the other end anchored in a casing 43. This coil spring will be wound up when the door is open and thus when the door closes by the engagement with the arm 21 as heretofore indicated the spring will slowly bring 40 the door to a closed position.

When the screen door is opened it moves the chain 30 by abutting the member 18 and will position the parts as shown in Figure 1 moving the bell crank 23 in a position to prevent the spring 42 from moving the chain back to the dotted line position shown in Figure 1 after the door 28 has been free from the device as illustrated in Figure 8, that is the projection 24 will engage in a notch in 50 one link of the chain from which it will be raised when the door slams closed and hits the arm 21 thereby swinging the member 19 so that the arm 22 raises the bell crank 23 to disengage the projection 24 from said notch 55 in the chain 17.

It is thought that the construction, operation, and advantages of this invention will now be clearly understood without a more detailed description thereof. The present 60 embodiment of the invention has been dis-

closed in detail merely by way of example since in actual practice it attains the features of advantage enumerated as desirable in the statement of the invention and the above description. It will be apparent that changes 70 in the details of construction, and in the combination and arrangement of parts may be resorted to without departing from the spirit and scope of the invention as herein-after claimed or sacrificing any of its advantages. 75

Having thus described the invention, what I claim as new and desire to secure by Letters Patent is:—

1. A device of the class described including, in combination, a frame, a pair of sprockets mounted in the frame, a chain trained over the sprockets, door engaging means on the chain, a shaft extending from one of the sprockets, a cylinder on said shaft having a notch with a cam surface adjacent thereto, a spring pressed projecting member mounted in the cylinder adjacent the cam surface, a disc on the shaft, a drum on the disc about the cylinder so that when the cylinder rotates in one direction, said spring pressed member will be projected and wedged between the cam surface and the drum to rotate the drum and disc therewith, and a centrifugal brake mechanism associated with the disc. 85

2. A device of the class described including, in combination, a frame, a pair of sprockets mounted in the frame, a chain trained over the sprockets, door engaging means on the chain, a shaft extending from one of the sprockets, a cylinder on said shaft having a notch with a cam surface adjacent thereto, a spring pressed projecting member mounted in the cylinder adjacent the cam surface, a disc on the shaft, a drum on the disc about the cylinder so that when the cylinder rotates in one direction, said spring pressed member will be projected and wedged between the cam surface and the drum to rotate the drum and disc therewith, a pair of weight arms pivotally mounted on the disc, spring means connecting the free ends of the arms, and a casing disposed about the arms and being stationary so that upon rotation of the disc the arms will be extended out into frictional engagement with the casing by centrifugal force. 90

3. A device of the class described including, in combination, a frame, a pair of sprockets mounted in the frame, a chain trained over the sprockets, door engaging means on the chain, a shaft extending from one of the sprockets, a cylinder on said shaft having a notch with a cam surface adjacent thereto, a spring pressed projecting member mounted in the cylinder adjacent the cam surface, a disc on the shaft, a drum on the disc about the cylinder so 105

that when the cylinder rotates in one direction, said spring pressed member will be projected and wedged between the cam surface and the drum to rotate the drum and disc therewith, a pair of weight arms pivotally mounted on the disc, spring means connecting the free ends of the arms, and a casing disposed about the arms and being stationary so that upon rotation of the disc 10 the arms will be extended out into frictional engagement with the casing by centrifugal force, spring means associated with said shaft to be wound up upon the shaft being moved when a door is open, and catch 15 means associated with the chain holding it in a predetermined position after the door

has been opened so as to hold said spring means wound up, said last mentioned means being releasable upon the closing of the door.

4. A device of the class described including a chain, means for mounting the chain for movement in a predetermined orbit, a door-engaging means on the chain, a braking mechanism, and means operatively connecting the braking mechanism with the chain, said braking mechanism comprising means whereby it will retard the movement of the chain in one direction only.

In testimony whereof I affix my signature.

FRED HENSEL.
